UNITED STATES PATENT OFFICE.

CHARLES J. NASH, OF CHICAGO, ILLINOIS, ASSIGNOR TO UNIVERSAL DRAFT GEAR ATTACHMENT CO., A CORPORATION OF ILLINOIS.

YOKE FOR DRAFT-GEAR.

1,137,348.

Specification of Letters Patent. Patented Apr. 27, 1915.

Original application filed October 9, 1911, Serial No. 653,676. Divided and this application filed August 16, 1913. Serial No. 785,014.

To all whom it may concern:

Be it known that I, CHARLES J. NASH, a citizen of the United States, and resident of Chicago, county of Cook, and State of Illinois, have invented certain new and useful Improvements in Yokes for Draft-Gear, of which the following is a specification, and which are illustrated in the accompanying drawings, forming a part thereof.

10 The invention relates to draft gear yokes of the standard M. C. B. type, which are substantially U-shaped, and particularly to the rear end of such yokes; the object of the invention being to provide great strength 15 at this portion of the yoke without increasing the weight or thickening the walls.

This application is a division of my application Serial No. 653,676, filed October 9th, 1911.

20 While the invention is illustrated in connection with a yoke adapted for use with the so-called tandem draft gear, it is equally adapted for use in connection with single draft gears, as it pertains to that portion 25 of the yoke which is brought into service only by pulling stresses.

In the accompanying drawings, Figure 1 is a detail longitudinal vertical section of a railway car taken between the center sills 30 thereof, and showing the draft rigging in side elevation; and Fig. 2 is a view in perspective of the yoke.

There is shown in the drawings a portion of the floor of a car at 10, one of the center 35 or draft sills at 11, the shank and butt end of the coupler at 12, the yoke at 13, follower plates at 14, 15, 16, 17, forward and rearward springs at 18, 19, an intermediate bridge or pair of stops integral with the

yoke at 20, and a carry iron for supporting 40 the draft mechanism at 21.

The yoke comprises the usual top and bottom longitudinal members, the forward ends of which are adapted to be attached to the butt of the coupler 12, as shown, by rivets or 45 by any other suitable means. At their rearward ends the top and bottom members of the yoke are curved inwardly, as shown at 22, 23, these inturned portions being united by a web 24 which forms a seat or bearing 50 for the rearward follower 17. If desirable, the rear end of the yoke may be further strengthened by fillets 25, only one of which is clearly shown in the drawings, crossing the recesses formed by the inturned portions 55 22, 23, of the longitudinal members.

This form of construction of the inner end of the yoke avoids the abrupt angles at the ends of the longitudinal members, which have heretofore been the weak points in devices of this character, and this without the massing of metal with consequent danger of weakening the casting.

I claim as my invention—

1. A yoke for draft gears comprising a 65 pair of parallel arms having their inner ends curved inwardly and forwardly and united by a web section, the distance spanned by the web being less than the distance between the parallel arms. 70

2. A yoke for draft gears comprising a pair of parallel arms having their inner ends curved inwardly and forwardly and united by a web section.

CHARLES J. NASH.
